DESIGN FOR AN AUTOGRAPHIC REGISTER

Carl W. Brenn, Montclair, N. J., and Arthur A. Johnson, Bridgeport, Conn., assignors to Autographic Register Co., Hoboken, N. J.

Application May 2, 1936, Serial No. 62,418

Term of patent 7 years

To all whom it may concern:

Be it known that we, Carl W. Brenn and Arthur A. Johnson, citizens of the United States, and each residents respectively of Montclair, county of Essex, and State of New Jersey, and of Bridgeport, county of Fairfield, and State of Connecticut, have invented a new, original, and ornamental Design for Autographic Register, of which the following is a specification, reference being had to the accompanying drawing, forming part thereof.

Fig. 2 is a top view of the same.

Fig. 3 is a side view of the same.

Fig. 4 is a front end view of the same.

We claim:

The ornamental design for an autographic register, as shown.

CARL W. BRENN.
ARTHUR A. JOHNSON.
